UNITED STATES PATENT OFFICE.

ROBERT G. PILKINGTON, OF CHICAGO, ILLINOIS.

SHACKLE.

Application filed November 10, 1919. Serial No. 336,800.

To all whom it may concern:

Be it known that I, ROBERT G. PILKINGTON, a citizen of the United States, residing at Chicago, in the county of Cook and State 5 of Illinois, have invented certain new and useful Improvements in Shackles, of which the following is a specification.

My invention relates to a shackle and more particularly to a shackle which is used 10 primarily in connection with leaf springs on vehicles of various types.

Shackles of this general type are provided with two weight carrying members, these usually being bolts or pins, one acting 15 as a pivotal connection between the shackle and a bracket secured to the under-frame of the vehicle and the other as a pivotal connection between the shackle and the spring. These members are held in parallel relationship by suitable connecting links.

The primary object of my invention is the provision of a shackle of simple and strong construction, inexpensive to make, 25 and which may be easily and quickly disassembled and repaired should one of its parts break.

A further object of my invention is to form the connecting links for the shackle 30 separately so that the sides of the links may be ground or otherwise finished in relatively large quantities conveniently and quickly.

A further object of my invention is to provide a shackle in which the weight carrying members or pins are held in position and against relative movements by improved key retaining means associated with one or both of the connecting links, the 35 pins preferably being of one diameter throughout.

A further object of my invention is to provide a shroud or housing for the shackle in combination with the side connecting 45 links and weight carrying pins so formed that it will engage and hold the pins against relative movements and also prevent deformation of the shackle.

Still another object of my invention is to provide a shackle in which the weight carrying pins, in combination with the key retaining means, are formed so that after becoming worn on one side they may be turned partially, thereby substantially increasing the usefulness of the pins.

The invention consists in the novel ar-

rangements, constructions and devices to be hereinafter described and claimed for carrying out the above stated objects and such other incidental objects as will appear from the following description of certain preferred embodiments of the invention illustrated in the accompanying drawings, in which—

Fig. 1 is a perspective view illustrating a fragmentary portion of a leaf spring connected to a bracket secured to the under-frame of a vehicle by means of a shackle embodying the principles of my invention.

Fig. 2 is a side elevational view of the shackle shown in Fig. 1.

Figs. 3 and 4 are sectional views taken on the lines 3—3 and 4—4, respectively, of Fig. 2.

Fig. 5 is a side elevational view of a shackle illustrating a modified form of pin retaining means.

Fig. 6 is a side elevational view of a shackle illustrating a further modification of pin retaining means, the latter serving also to prevent deformation of the shackle, and

Fig. 7 is an end elevational view, on a reduced scale, of the shackle shown in Fig. 6.

Like characters of reference designate like parts in the several views.

The shackle comprises weight carrying pins 10 and 11 fastened together by suitable connecting links 12, 12, the pins 10 and 11 being held against relative movements by suitable key retaining means designated generally by the reference numeral 13. The pin 10 is adapted to pass through a depending lug 14 formed on a bracket member 15, which may be of any suitable form or shape, secured to the underframe 16 of the vehicle. The lower pin 11 is adapted to be inserted through the loop formed on the end of the leaf spring 17.

The weight carrying pins 10 and 11 may be held in position and against relative movements in a number of ways, only certain preferred forms being shown in the drawings. In Figs. 1 to 4 inclusive, the retaining means 13 comprises a U-shaped member, the arms 18 of which are adapted to embrace the connecting links 12. The pins 10 and 11 are formed preferably adjacent each end, with flat bearing surfaces, preferably in the form of transverse, flat bottomed grooves 19, which are formed in

any suitable manner and adapted to receive the edges of the arms 18 of the retaining member 13. In this form the pins 10 and 11 are turned so that the flat bearing surfaces or grooves 19 face each other, the top and bottom edges of the arms 18 being machined so that the arms will fit accurately and tightly between the pins 10 and 11 as clearly shown in Fig. 2. The arms 18 are each preferably secured to the connecting link 12 by means of a cap screw 20, a lock washer 21 being provided to prevent the screw from working loose. Each of the arms 18 constitutes a key plate which effectively engages the flat bearing surfaces on the pins 10 and 11 and holds the pins against relative movement. Preferably the pins 10 and 11 are formed on each end with oppositely disposed flat bearing surfaces on grooves 19 so that after becoming worn on one side the pins may be turned partially thereby substantially doubling the life of the pins. If desired passageways 22 may be formed in the pins 10 and 11 and oil cups 23 connected therewith for the purpose of lubrication.

It will be observed that the pins 10 and 11 are generally of one diameter throughout which reduces the machine work to a minimum. In disassembling the device it is merely necessary to take out the screw or screws 20, as the case may be, drive the key retaining means backwardly out of engagement with the pins 10 and 11 and then drive the connecting links off the ends of the pins, these links not being otherwise connected to each other. This operation may be done quickly and easily even though the shackle be under a heavy load. The U-shaped retaining member 13 tends to prevent deformation of the shackle, that is to say, it prevents relative movements of the connecting links 12.

In the form shown in Fig. 5 the pins 10 and 11 are turned so that the bearing surfaces 19 face laterally these being substantially parallel with the vertical axis of the shackle. The arms 18 of the key retaining member 13 in this form are wider and shorter than in the form first described, and are adapted to bear against the bearing surfaces 19 when in the position last mentioned.

In the form shown in Figs. 6 and 7 the member 13 is in the form of a shroud or a dish-shaped housing, the ends 23 thereof being bent around at substantially right angles to the back web 26 and also being cut away in the center so that the inner opposite faces 24 will bear against the outer bearing surfaces 19 of the pins 10 and 11, the sides 25 thereof also being bent around at substantially right angles to the back web 26 to provide stiffening means. This form of housing, therefore, is U-shaped both with respect to its vertical axis and its horizontal

axis. This form of shackle is particularly useful on trucks which are subjected to heavy duty. The dish-shaped member 13 effectively prevents relative movements of the pins 10 and 11 and of the connecting links 12.

The pins 10 and 11 are preferably formed of steel, case hardened and ground to the proper diameter. The connecting links 12 are preferably drop forgings. The members 13 are preferably steel stampings. There are several advantages in making the connecting links separately. For example, they may both be formed from the same pattern or die; a large quantity of them may be held by a magnetic clutch and one face held by a magnetic clutch and one face ground, the position reversed and the other face ground, the finishing operation thus being reduced to a minimum, and the same links may be used for springs of various widths.

It will be obvious to those skilled in the art that various modifications may be made without departing from the spirit of my invention, and I do not intend to limit the invention to the constructions, arrangements and devices shown and described except only in so far as certain of the appended claims are specifically so limited.

I claim:

1. A shackle comprising a pair of links formed with registering perforations, weight carrying pins adapted to be inserted in said perforations, said pins each being formed with flat surfaces, a U-shaped retaining member associated with said links, certain edges of the arms of said member bearing against the respective flat surfaces of the pins, and means to secure said member against movement relative to said links, for the purpose described.

2. A shackle comprising a pair of links formed with registering perforations, weight carrying pins adapted to be inserted in said perforations, said pins each being formed on each end with a transversely extending groove, a U-shaped retaining member associated with said links, certain edges of the arms of said member bearing against the bottoms of said respective grooves, and means to secure said member against movement relative to said links, for the purpose described.

3. A shackle comprising a pair of links formed with registering perforations, weight carrying pins adapted to be inserted in said perforations, said pins each being formed with a flat surface arranged to face outwardly, a U-shaped plate, the arms of which are adapted to embrace the ends of said pins, the inner sides of the arms bearing against said flat surfaces and means to secure the plate to one of said links.

4. A shackle comprising a pair of links formed with registering perforations,

weight carrying pins adapted to be inserted in said perforations, said pins each being formed with a flat surface on each end arranged to face outwardly, a U-shaped retaining member adapted to embrace said links, the arms of which are also U-shaped and adapted to embrace the ends of said pins, the inner sides thereof bearing against said flat surfaces, and means to secure the retaining member to said links.

5 10 15 20 25 30 35 40 45 50 55 60 65 70 75 80 85 90 95 100 105

5. A shackle comprising a pair of links formed with registering perforations, weight carrying pins adapted to be inserted in said perforations, said pins each being formed with a flat surface on each end arranged to face outwardly, a rectangular dish-shaped housing, the ends of which are adapted to embrace said links, said end portions being U-shaped and adapted to embrace the ends of said pins the inner sides thereof bearing against said flat surfaces, and means to secure the housing to said links, the sides of said housing being bent at substantially right angles to the main web of the housing.

6. A shackle comprising a pair of links formed with registering perforations, weight carrying pins adapted to be inserted in said perforations, said pins each being formed with a flat surface on each end, a rectangular dish-shaped housing, the ends of which are adapted to embrace said links, said end portions being formed so as to bear against the flat surfaces on said pins, means to secure the housing to the links, the sides of the housing being formed at substantially right angles to the main web of the housing.

7. A shackle comprising a pair of links formed with registering perforations, weight carrying pins adapted to be inserted in said perforations, said pins each being formed with a flat bottomed groove, a retaining member adapted to embrace said links, the arms of which are adapted to bear against the bottoms of said grooves, and means to secure said member to one of said links.

8. A shackle comprising a pair of links formed with registering perforations, weight carrying pins adapted to be inserted in said perforations, said pins each being formed with a flat bottomed groove adjacent each end, a rectangular dish-shaped housing, the ends of which are adapted to embrace said links, said end portions being formed

so as to bear against the flat bottoms of said grooves, means to secure the housing to the links, the sides of the housing being formed at substantially right angles to the main web of the housing.

9. A shackle comprising a pair of independent links formed with registering perforations, weight carrying pins adapted to be inserted in said perforations, said pins each being formed with a flat surface, a retaining member adapted to embrace said links, the arms of which bear against the flat surfaces of the pins, and means to secure said member to one of said links whereby said pins are held against relative movement.

10. In a shackle of a class described the combination of a pair of links formed with registering perforations, weight carrying pins adapted to be inserted in said perforations, said pins each being formed with a flat surface, a U-shaped retaining member adapted to embrace said links, the arms of which are adapted to bear against the flat surfaces of the pins and means to connect the arms to the associated links whereby said pins and said links are held against relative movement.

11. A shackle comprising a pair of links formed with registering perforations, weight carrying pins adapted to be inserted in said perforations, a U-shaped retaining member associated with said links, and means to secure said member against movement relative to said links, said pins being of uniform diameter throughout their length and provided with bear surfaces adapted to co-operate with bearing surfaces on said member, for the purpose described.

12. A shackle comprising a pair of links formed with registering perforations, weight carrying pins adapted to be inserted in said perforations, a dish-shaped retaining member associated with said links the end and side portions of which are formed at substantially right angles to the main web thereof, and means to secure said member against movement relative to said links, said pins being of uniform diameter throughout their length and provided with bearing surfaces adapted to co-operate with bearing surfaces on said member, for the purpose described.

ROBERT G. PILKINGTON.
